METHOD OF AND APPARATUS FOR
ASSEMBLING PACKAGES

Ronald R. Brogden, Orlando, Fla., assignor to
Bank of The Manhattan Company, New York,
N. Y., a corporation of New York, trustee

Application May 15, 1936, Serial No. 79,879

12 Claims. (Cl. 93—6)

This invention relates to a method of and apparatus for assembling packages and particularly packages of the type including an elastic binder for closing the package.

5 In packaging certain commodities it is often desirable to secure a container having a separate or attached cover-forming portion or a wrapper about the contents by an endless elastic binder. Where a binder is to be applied to a container 10 or package having certain shapes as, for example, triangular, it is difficult to apply the binder to the container or package in such a way that it is uniformly tensioned and is neatly and evenly disposed about the container or 15 package.

According to the present invention, an elastic binder is maintained in the form of an extended closed loop and the articles to which the binder is to be applied are disposed over the elastic 20 binder in predetermined relation therewith. A loop or bight at one end of the binder is engaged over an apex or corner portion of the article from one direction and another loop or bight at the other end of the binder is drawn 25 over the apex or corner portion from the opposite direction thereby to engage the binder on the article with the portion of the binder intermediate said loops or bights passing across two opposite faces of the article and forming a loop 30 or loops engaging apexes or corners other than the first-mentioned apex or corner.

The invention also provides suitable apparatus for conveniently applying the binder to the package or container. Preferably, the apparatus 35 includes a suitable support having a portion, which may be formed as a platform, adapted to receive the package or container and an abutment adjacent the package-receiving portion for limiting movement of the package. A plurality of upstanding pillar-like members disposed on opposite sides of the package-receiving 40 portion are adapted to receive the binder and maintain it in a convenient loop form for applying it to the package.

45 The package-receiving portion of the support may be inclined, thereby to support a container in such a way that when rollable articles are disposed therein they tend to adjust themselves into an evenly distributed layer or layers in the container. Upstanding abutments may also be provided on the apparatus for bending up side-forming portions of a box blank and for retaining the side-forming portions in upstanding 50 relation during filling of the container, whereafter the sides may be suitably secured in up-

standing position. The upstanding pillars may be rotatably supported whereby, when the elastic binder is trained around the pillar, the latter will rotate a sufficient amount to equalize the tension on all portions of the binder. The various portions of the apparatus may be made adjustable to accommodate packages and containers of various sizes and shapes.

Various other features and advantages of the invention will be apparent from the following 10 particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying 20 drawings forming a part thereof, in which:

Fig. 1 is a top plan view of one form of apparatus suitable for carrying out the invention;

Fig. 2 is a side elevational view of the apparatus shown in Fig. 1;

Fig. 3 is an enlarged fragmentary cross-sectional view taken along line 3—3 of Fig. 1;

Fig. 4 is a perspective view of the apparatus, showing an electric binder and a partially filled box in position on the apparatus preparatory 30 to applying the binder to the container;

Fig. 5 is a view similar to Fig. 4 showing the container closed and the binder partially applied thereto;

Fig. 6 is a view similar to Fig. 4 showing the 35 binder completely applied to the container;

Fig. 7 is a perspective view showing the completed package after it has been taken from the apparatus;

Fig. 8 is a perspective view of a modified form 40 of apparatus showing the binder in position on the apparatus and a box blank disposed above the apparatus in position to be registered therewith;

Fig. 9 is an enlarged fragmentary cross-section 45 taken along line 9—9 of Fig. 8;

Fig. 10 is a view similar to Fig. 8, the box blank being shown as set up to form a box;

Fig. 11 is a view similar to Fig. 10, the box blank being shown assembled with cover and 50 the binder partially applied to the container;

Fig. 12 is a view similar to Fig. 10, the binder being shown as completely applied to the container; and

Fig. 13 is a perspective view showing the com- 55

pleted package after it has been taken from the apparatus.

Referring now to Figs. 1, 2 and 3, there is shown one form of apparatus especially well adapted for forming a package from a box-like container of generally triangular shape, which apparatus will be described in connection with my process, for the purpose of illustrating the process.

10 The apparatus includes an elongated, generally rectangular support or frame 1 which may be formed of suitable rigid material such as wood, metal or others and may conveniently have longitudinally extending base rails or legs 15 2. Mounted on the support 1 are upstanding pillars or studs 3, 4 and 5. The pillar 3 is suitably mounted adjacent one end of the support and pillars 4 and 5 are mounted adjacent the other end of the support and are in alignment 20 along a line perpendicular to the longitudinal center line of the support 1.

Each pillar, as for example pillar 5 (shown more in detail in Fig. 3), may be formed for retaining the elastic binder in the desired formation and may comprise a cylindrical roller 10 having secured therein a bushing 11 carrying a ball bearing 12. Extending through the bearing 12, which extends through an elongated slot 16 in the support 1, is a bolt 15 which is secured 30 by a nut 17; washers 18 and 19 are interposed between the support 1 and the bearing 12 and nut 17 respectively. The pillar 3 may be formed similarly to the pillars 4 and 5 and may be supported on a bolt 18 passing through an elongated slot 20. The elongated slots 16 and 20 permit considerable adjustment of the position of the pillars longitudinally of the support.

40 Adjacent the pillars 4 and 5 is a supporting portion for a container or package to be wrapped, which portion may be formed as a platform 25 suitably attached to the support by screws 26 and having an inclined upper face.

45 Adjacent the edge of the platform 25 nearest the pillar 3 is suitable abutment means which may be a plurality of upstanding studs 27 each having a threaded portion 28 and a head 29 and threaded into an opening 30 in the support 1. The abutment means serves to retain the package or container in suitable position on the platform and prevents it from being displaced during the application of the binder hereinafter described.

50 Referring to Fig. 4, the apparatus is shown in connection with one form of box which can be conveniently packaged according to the present method and with the present apparatus. The box 40 may comprise a bottom 41 of generally triangular shape and sides 42, 43, 44 and 45 upstanding from the edges of the bottom 41. As 55 shown in Fig. 5 a suitably formed cover 50 with a depending flange 51 may be provided for closing the box 40.

55 Prior to filling the box, an elastic binder 60 which preferably is a rubber band is trained over the pillars 3, 4 and 5, which maintain the binder 60 in the form of an extended closed loop of generally triangular form having a base 61 extending between the pillars 4 and 5, sides 62 and 63 extending from the base to the pillar 3, and an apex 64 engaging the pillar 3. The portions 61 and 64 of the rubber band thus positioned constitute end bights, both of which, as will presently appear, are to be looped in opposite directions over that corner of the container shown adjacent pillars 4 and 5 in Fig. 4.

5 Since the pillars 3, 4 and 5 are rotatably mounted, the binder will automatically adjust itself when trained thereover so that all portions are uniformly tensioned. The pillars are positioned relatively to the platform and to each other suitably so that the lengths of the several portions of the binder are in ratio to (i. e. properly correlated to) the corresponding distances over which they respectively extend when applied to the container. The pillars 3, 4 and 5 may be adjusted so that the respective portions of the binder are of suitable length for engaging the corresponding portions of containers of various sizes, and thus the binder, when applied, is under substantially uniform tension 10 throughout its length.

10 The container 40 is disposed on the platform 25 and its base side wall 43 bears against the abutment studs 27, its opposed corner or apex portion being in general alignment with the end bights 61 and 64 of the binder. The articles 46 to be packaged are then inserted and the cover 50 is disposed on the container. Where the content comprises rollable articles as, for example, marbles, candies or other generally globular articles, they will tend to roll toward the side wall 43 and thus adjust themselves into evenly distributed compact layers.

20 The cover 50 is applied to complete the container and the base portion 61 of the binder 60 is carried up over and engaged with the adjacent apex portion of the container, the base side wall 43 of the container being meanwhile held firmly against abutment studs 27 by the tension of the binder which is still looped over pillar 3. Thereafter, the apex portion or bight 64 of the binder is carried up over and across the top of the container, the sides 62 and 63 engaging the side wall 43 and adjacent portion of the top and the apex 25 64 is carried over and engaged under the same aforesaid apex portion of the container.

30 Referring to Figs. 6 and 7 it will be seen that the binder 60 engages the container in a plurality of loops or bights 65, 66, 67 and 68, the bights 65 and 66 being substantially those portions, 61, 64, of the binder referred to hereinabove as end bights. The loop 65 engages the apex of the container from the top and the loop 66 engages it from the bottom. The loops 67 and 68 engage the other two corners of the container respectively. Thus, all the corners of the container are engaged by the binder in such a way that the binder is automatically locked on the container and retains the cover thereon.

35 Various modifications may be made in the process and apparatus in order to adapt the inventive concept to the applying of a binder to various types of containers or packages. Referring to Fig. 8, there is shown a second form of apparatus which is especially well adapted for setting up a 40 box blank to form a container and applying an elastic binder thereto.

45 The apparatus may be broadly similar to that shown in Fig. 1 and may include a support 101 having pillars 103, 104 and 105 rotatably mounted 50 thereon. Each pillar may be formed and supported in a manner generally similar to the pillar 3 of Fig. 1.

55 Disposed on the support 101 and near the pillars 104 and 105 is a platform 125 which may be constituted by a substantially flat plate or block having a generally horizontal surface and secured to the support 101 as by means of screws 126. Upstanding from the support 101 adjacent one edge of the platform 125 is suitable abutment means 70 75

such as spaced studs 127 suitably secured in the support 101.

Upstanding from the support 101 adjacent the opposite corners of the platform 125 from the 5 studs 127 are studs 135. Each stud 135 may have a threaded portion 128 extending through an elongated opening 136 in the support 101 and may be secured by an integral head 130 and a wing nut 137, washers 132 and 133 being interposed between 10 the support, and the head 130 and the nut 137. If desired, the platform 125 may be recessed as indicated at 138 to accommodate the studs 135.

Referring now to Fig. 8, there is shown one 15 form of blank which can be conveniently set up with the aid of the apparatus to form a box, and then filled and the binder applied, while the box is in position on the apparatus.

By way of illustration the blank 139 is shown 20 having a generally triangular bottom section 141 and side sections 142, 143 and 144, bendable about score lines 146, 147 and 148 respectively. The blank is set up by registering it over the platform 125 and depressing it until the bottom section 141 rests upon the face of the platform 125. During 25 the downward movement the studs 127 engage the section 143 and bend it up along score lines 147 and the studs 135 engage the sections 142 and 144 and bend them up along score lines 146 and 148 respectively. Thus a set-up box 140 is formed as 30 shown in Fig. 10.

Prior to setting up the box, an endless binder, which may be a rubber band 160, is trained over the pillars 103, 104 and 105 in the form of an extended triangle having a base 161, elongated 35 sides 162 and 163 and an apex 164.

After the box 140 has been set up, it may be filled in a convenient manner and thereafter closed by a suitable cover 150 having a side flange 151 adapted to retain the side walls of the box 40 140 in upstanding position. If desired, flange 151 may extend substantially to the bottom of the box thereby providing a container having side walls of double thickness.

The binder 160 is applied to the container by 45 carrying the base portion 161 up over the apex of the container to engage therewith. Thereafter the apex portion 164 is drawn over and across the top of the closed container and carried under the apex portion and engaged therewith. Referring to Figs. 12 and 13 it will be seen that the binder 160 engages the closed container in a plurality of loops, the loop 165 engaging the apex of the container from the top, the loop 166 engaging the apex portion from the bottom, and the loops 50 168 and 169 engaging the base corner portion of the container respectively.

Various modifications in the method and apparatus may be made as will be apparent to those skilled in the art. For example, although preferably the base portion of the binder is engaged with the container prior to the apex portion of the binder with the container, this procedure may be reversed and desirable results obtained. Although the method is primarily for use with containers or packages of triangular or approximately triangular shape, in some cases it may be used with value in connection with containers or packages of other shapes as, for example, square, lozenge, or others having corners or projecting 55 portions for receiving portions of the binder.

The method is applicable to the completing of packages which have been previously assembled, in which case the assembled package is disposed on the platform and the binder applied in the 70 manner described. Various modifications in the

platform and abutments may be made to adapt the apparatus for setting up containers of other and more complex construction than the illustrative container disclosed.

The method is rapid and efficient and insures 5 that the binder is applied with uniform tension and is neatly and evenly positioned on the container or package. The manipulation of the process with apparatus of the type disclosed is relatively simple and can be carried out by relatively unskilled labor with desirable results.

While certain novel features of the invention have been disclosed and are pointed out in the annexed claims, it will be understood that various omissions, substitutions and changes may be made 15 by those skilled in the art without departing from the spirit of the invention.

What I claim is:

1. The method of applying an elastic binder to an article of generally triangular shape which 20 comprises disposing and maintaining an elastic binder in extended form to present end bights in predetermined spaced-apart relation, placing the article with one face cooperatively adjacent said binder intermediate said bights and with one apex 25 or corner portion in general alignment with said bights, and looping said bights oppositely around said apex or corner portion.

2. The method of applying an endless elastic binder to an article of generally triangular shape 30 which comprises disposing the elastic band in extended loop form, equalizing the tension in all portions of the band, disposing the article on the band, engaging one end of the loop over a corner of the article and drawing the second end of the 35 loop over and across the top of the article and engaging it under said corner of the article from a direction opposite to said first end of the loop.

3. The method of applying an endless elastic binder to an article having a generally triangular 40 shape which comprises maintaining the binder in extended, generally triangular shape, disposing the article on the binder in reversed apex to base relation adjacent the base of said binder, engaging the base of the binder over the apex of 45 the article, and drawing the apex of the binder over and across the top of the article and engaging it under the apex of the article.

4. The method of applying an endless elastic binder to an article having a generally triangular 50 shape which comprises maintaining the binder in extended generally triangular shape, disposing the article on the binder in reversed apex to base relation adjacent the base of said binder, drawing the apex of the binder over and across 55 the top of the article and engaging it under the apex of the article, and engaging the base of the binder over the apex of the article.

5. The method of applying an endless elastic binder to an article having corner portions, which 60 comprises stretching an endless elastic binder to such length that the several portions thereof are of suitable length to engage the corresponding portions of the article to which the binder is to be applied, the binder so stretched presenting two 65 end bights, establishing contact between a face of the article and a portion of the stretched binder intermediate said bights, with a corner portion of said article in general alignment with said bights, and looping both bights over said corner portion 70 in opposite directions.

6. Apparatus for applying an elastic binder to a package or article comprising a support, means including a plurality of spaced upstanding pillars mounted on said support for maintaining an elas- 75

tic binder in extended loop form, and means including a transverse abutment disposed intermediate said pillars for maintaining an article in position to be engaged by said binder when said binder is removed from said pillars.

7. Packaging apparatus comprising a support, means including an upstanding abutment for forming up the sides of a box blank when the blank is forced into engagement with the support in a predetermined manner, and means including upstanding abutments on opposite sides of said first abutment for receiving a binder to be applied to said box, and maintaining said binder in extended loop form.

15. 8. Apparatus for applying an endless elastic binder to an article of generally triangular shape comprising a support, means for mounting an endless elastic binder on said support in the form of an elongated triangle, and an abutment upstanding from said support adjacent the base of the triangle formed by a binder on said mounting means, for maintaining an article in position to receive a binder from said mounting means.

9. Apparatus for applying an endless elastic binder to an article of generally triangular shape comprising a support, means including rotatable pillars upstanding from said support for mounting an endless elastic binder on said support in the form of an elongated triangle, in which all portions of said binder are under substantially equal tension, and an abutment upstanding from said support adjacent the base of the triangle

formed by a binder on said mounting means, for retaining an article in position to receive a binder from said pillars.

10. Apparatus for applying an elastic binder to a package or article, comprising a supporting base, and a plurality of spaced-apart retaining members mounted on said base, said members being adapted and arranged to retain an endless elastic binder trained about them under tension in the form of an elongated loop and to permit equalization of such tension throughout such loop, said base being adapted to support a package or article over said loop at a locality intermediate the ends thereof.

11. Apparatus as defined in claim 10, wherein the mounting of at least one of said retaining members is adjustable to vary the relative spacing of said members along said base and thereby accommodate tensioned binder loops of different lengths.

12. Apparatus for applying an elastic binder to a package or article of generally triangular shape, comprising a supporting base, and three retaining and tension-equalizing members rotatably mounted thereon in upright position, in the form of an elongated triangle, and adapted to retain an endless elastic binder trained about them under tension in the form of an elongated loop, said base being adapted to support a package or article over said loop at a locality intermediate the ends thereof.

RONALD R. BROGDEN.
